GAME

Herbert G. Breitenstein, Chicago, Ill., assignor
to Raymond T. Moloney, Chicago, Ill.

Application September 27, 1934, Serial No. 745,745

6 Claims. (Cl. 273—122)

The invention relates to improvements in a game of the ball rolling and trapping type.

Such games comprise a board inclined from the horizontal and having ball receiving holes therein for game scoring purposes. A number of balls are projected one at a time by a manually operable projector from the lower to the upper end of the game board. When the force imparted to each ball in so projecting it has been spent, the balls move by gravity down the board, and if skillfully projected become trapped by holes or pockets of various kinds having numbered score values.

The main object of the present invention is to provide improvements in such games which will create unusual ball routing and trapping action to enhance player interest and enthusiasm, thus affording the maximum player amusement.

Another object is to provide a game board in which a projected ball may gravitate theredown and into a hole therethrough, and thence roll beneath the board and out of the player's view, to a mechanism that will automatically catapult the said ball upwardly through the board and uphill thereon to be trapped by a higher value score pocket or hole.

Still another object is to provide an improved game board play field arrangement apportioned into separate score areas or zones, whereby when a ball is trapped in a first area it moves under the board as above stated and when it is thereupon catapulted onto the board again it goes into play in another score area.

Also it is an object to provide such a game board in which a ball may drop through a hole in the board, roll thereunder to a catapult, be catapulted back onto the board into a different score area, drop through the board again and roll thereunder to a different catapult, which is actuated to catapult the ball to a third scoring area of maximum value.

Another important object is to provide an improved form of catapult which is to be automatically actuated when a ball rolls thereon.

It is also an object to provide a ball passage on the board closed by a switch device to prevent movement of a ball through the passage, said switch being controlled by a subsequently played ball to permit movement of the first ball through the passage.

Other important objects of the invention will be apparent to those skilled in this art as the disclosure is more fully made.

Briefly such important and desirable objects may be achieved by the practicable example of

the game illustrated in the accompanying drawings, wherein generally the inclined game board embodies a plurality of separated scoring areas or zones so that a projected ball must first be trapped in the first zone to create the action heretofore described of successively catapulting the ball. Assuming a ball drops through a hole in the first zone, it then rolls down an under panel and is guided onto a catapult which is automatically and electrically operated by the ball itself to cause the catapult to throw said ball back onto the main board and into the second ball trapping zone. If the ball drops through the proper hole in the second zone it moves under the game board to another catapult which is similarly actuated to throw the ball upwardly and roll it back onto the game board again, but this time in a third score zone which in the present embodiment constitutes the maximum scoring area. Other features also are involved and will be discussed in detail later. Obviously, in such game, with the balls disappearing from view and then suddenly catapulting onto the board again, a maximum of player interest will be aroused.

In the drawings illustrating one desirable form, which the invention may assume in practice:

Figure 1 is a top plan view of the game contained in an appropriate cabinet;

Figure 2 is a plan view of the game with the top, or game board removed, to illustrate a thin metal, control plate immediately below the said top or game board;

Figure 3 is a detail plan view of the passage and ball switch feature;

Figure 4 is a view similar to Figure 3 to illustrate the position assumed by the switch or gate when it operates to let a ball move through the passage;

Figure 5 is a transverse cross sectional detail view through this ball switch structure taken along the line 5—5 of Figure 1, looking in the direction of the arrows;

Figure 6 is a plan view of the game as seen with the top board of Figure 1 and the metal control plate of Figure 2 removed to show the ball routing under panel.

Figure 7 is a detail, longitudinal sectional view through a trap door structure taken along the line 7—7 of Figure 1 looking in the indicated direction;

Figure 8 is a detail, longitudinal sectional view through mechanism to illustrate how certain movable parts function, as taken along the line 8—8 of Figure 6, looking in the direction of the arrows;

Figure 9 is a central, longitudinal, side, sectional view through the whole game taken along the line 9—9 of Figure 1, looking in the direction of the arrows;

5 Figure 10 is an enlarged longitudinal sectional view illustrating the catapult mechanism and taken along the line 10—10 of Figure 6, looking in the indicated direction; and,

10 Figure 11 is a longitudinal, detail, sectional view through a circuit closer taken along the line 11—11 of Figure 6, looking in the direction designated by the arrows.

15 As is usual in this art the game is enclosed in an elongated, or rectangular cabinet 15, having a front wall 16 at the player end, and a rear wall 17 at its other end. The cabinet 15 has a bottom or floor 18 and its open top is closed by the usual glass panel 19.

20 As shown best in Figures 1 and 9, the upper end of the cabinet just under the glass 19 carries a game board 20 inclined from the horizontal as shown, with its high end at the rear wall 17 and its lower end at the front wall 16. Adjacent the sides and upper end of the board 20 is mounted 25 as shown, a U-shaped marginal member 21 forming an oval track for the upper end of the play field on the top surface of the board 20. At the lower end adjacent the front wall 16 the board 20 carries a cut out plate 22 which along the 30 median line of the game is recessed to form a widening ball passageway 23 and on opposite sides thereof in symmetric formation are provided rounded bays 24. Within each bay 24 the board 20 is provided with a hole 25 and at the 35 front end of the passage 23 the board 20 is formed with a wide transverse slot 26 constituting the score pocket of maximum value as will later appear.

40 Between the left hand side (as viewed by the player) of the cabinet and the forward edge of the left hand bay 24 is a hood 27 carried on the board 20 and covering a large hole formed in the board through which a ball may be catapulted, as will later appear. In transverse alinement the 45 board 20 carries other catapult hoods 28, 29, 30, 31 and 32, there being a large catapult hole in the board 20 as heretofore described, one of such holes for example under the hood 29 being indicated at 33 in Figure 9 by dotted lines.

50 A longitudinal rail 34 runs from the right hand edge of the longitudinal hood 32, along the right hand side of the cabinet, and in spaced relation, to form a ball projection passage 35, which at its upper end is provided with a conventional form 55 of one way gate 36 made of light wire. A ball projector 37 operable by a handle 38 shoots balls one at a time through the passage 35, said balls passing through the gate 36 and emerging onto the upper end of the play field. The ball will 60 usually follow the oval track and rebound from a spring bumper 37 at the other side of the board 20. The gate 36 swings upwardly when the ball passes therethrough and engages the glass panel 19 to prevent it from swinging over dead center. Thus, the ball moves therethrough in only one direction as the gate instantly swings back by gravity to close off the passage 35.

65 From the left hand side of the hood 32 is extended a longitudinal rail 38 forming with the rail 70 34 a ball projection passage 39 leading from the hood 32 uphill on the board 20. The end of said passage 39 carries a gate 40 exactly like the gate 36 already described. By means of a curved division member, or partition 41 an oval track is 75 formed to lead balls coming through the gate 40

and direct them against a spring bumper 42 for rebounding action and gravitation down a side area or zone 43. Said zone 43 is further delineated by a longitudinal rail 44 leading to the right hand side of the hood 31, thus forming said 5 area coincident with the bay 24 on the right hand side, and running uphill on the board 20 not quite half way.

Contained within said zone 43 are two holes 45 and 46 formed through the board 20, with a division block 47 disposed between said two holes. In longitudinal alinement with the hole 46 and between it and the hole 25 at the lower end of said zone 43 is a barrel shaped member 48 simulating a gun or cannon. A hole is formed in the 15 board 20 directly adjacent the muzzle end of the gun 48, said hole normally being closed by a hinged trap door 49 carried by the board 20.

On the opposite, or left hand side of the board 20 is a curved division member 50 similar to the member 41 already described and serving the same purpose. A rail 51 leads from the hood 27 forming a ball passage 52 having a gate 53 exactly the same as the gate 40. A ball catapulted from under the hood 27 rolls uphill in the passage 52 over the board 20, through the gate 53, and is thence guided by the oval form of the division member 50 to rebound from a spring bumper 54 adjacent a rail 55 extending longitudinally to form a closed zone or area 56 which is the 30 counterpart of the right zone 43 already described. Within this zone are two holes 57, 58 separated by a block 59. Also, there is a cannon 60 and trap door 61 just as heretofore pointed out in connection with the zone 43.

35 The partition members 41, 50 are each extended in a curve toward the center by rails 61', 62 merging at their upper ends into a cannon member 63 of the same type as the cannons 48, 60. Thus, is formed an upper zone or area 63. At the muzzle end of the gun 63 (see Figure 9) is a trap door 64 pivoted at 65 in the forward end of an elongated hole 66 formed in the board 20 under said cannon 63. By means later to be described the door 64 is normally held closed, 45 as shown in Figure 9 so that a ball may be supported thereon. The structure of the trap doors 49, 61 is identical with that just described.

50 In longitudinal alinement with the cannon 63 and thereabove, the board 20 is provided with an electric circuit controlling hole 66 embraced by an ornamental block 67 to separate it from a second control hole 68 arranged in the board 20 thereabove. In this zone 63' are a pair of holes 69 and another pair of holes 70 all formed 55 through the board 20. Furthermore, on one side of the gun 63 the board 20 is formed with a hole 71 having a ball supporting seat 72 therein, and on the other side is a hole 73 having a seat 74 therein.

60 Extending longitudinally upwardly on the board 20 from between the catapult hoods 28, 29 is a rail 75 and similarly from between the hoods 30, 31 is extended a rail 76. These rails extend about as far up the board 20 as the bumpers 42, 65 54, where they are cross connected by a partition block 77 having its edge facing the front wall 16 formed with arcuate portions to direct balls projected thereagainst down a central passageway 78 formed by a pair of short longitudinal rails 70 79 extended respectively as shown in Figure 1 from the two inner catapult hoods 29, 20. Thus leading upwardly from the hood 29 is a longitudinal passage 80 formed between the rails 75, 79 and leading from the hood 30 is a similar 75

passage 81 formed between the one rail 79 and the rail 76. Each passage 80, 81 ends in a gate 82 similar to the gate 36 heretofore described. Thus, the small area at the upper end of the 5 passage 78 forms another separate play field zone.

Extending upwardly from each end of the block 77 are curved rails 83 conforming to the shape of the adjoining members 50, 41, to form still another zone 84 on the central portion of the board 10 20 as shown in Figure 1. The rails 55, 75 form a ball projection passage 85 leading uphill from the catapult hood 28 onto the upper end of the zone 84. Similarly the rails 44, 76 form a passage 86 leading uphill from the hood 31. At 15 the lower end of the zone 84 and directly in front of the partition 77 is a transverse slot 87 formed in the board 20. Immediately thereabove the board 20 is provided in said zone 84 with three holes 88 each having a ball supporting seat 89 20 and on opposite sides are two holes 90 to permit balls to fall through the board 20. In the upper end of said zone are a pair of converging spring fingers 91 which serve to direct balls to the several holes located therebelow.

25 On opposite sides of the board 20 and along the transverse diameter of the circle 61', 62 are curved rails 92 to form ball passages 93 each leading to a hole 94 in the board 20, as shown. These passages 93 lead from the zone 63' and 30 each includes, as shown in Figure 7 an elongated, longitudinally disposed, trap door 95 pivoted at 96 and arranged normally to close off a hole 97 in the board 20, and when in hole closing position to support a number of balls. Each door 35 95 includes a tail extension 98 for a purpose later to appear.

At the inner edge of each passage 93 is journaled a vertical rock shaft 99 as shown in Figure 5 which is projected downwardly through the 40 board 20, and each shaft carrying at its upper end a bell crank shaped switch 100, normally disposed in the position shown in Figure 3 to prevent balls from rolling down the passage 93 to the hole 94 at the lower end thereof.

45 The under side of the board 20 carries a number of pins 101, which as shown in Figure 2 carry a metal plate 102 provided with elongated slots 103 to enable the plate 102 which is supported by heads at the lower ends of the pins 101 to be longitudinally shiftable with respect to the board 50 20. This plate 102 at its forward edge is formed with a bracket 104 engageable by a conventional coil released slide 105. By this means the plate 102 is shifted.

55 This plate 102 is provided with the ball seats 72, 74, 89 heretofore described, and in addition, with a number of holes and slots to permit balls held on the game board 20 to drop through said plate 102 to a still lower, or ball routing panel 60 later to be described. For instance, forwardly of each seat 89 is a hole 107. Also below the slot 66 under the cannon 63 and trap door 64 is an elongated slot 108 formed in said plate 102. Within said slot 108 is a cross bar 109 to support 65 the tail of the trap door 64 as shown in Figure 9.

Under each trap door 95 the plate 102 has a slot 110 as shown in Figure 2, the rock shafts 99 projecting downwardly through said slots 110. The tail 98 of each trap door 95 as shown in 70 Figure 7 normally resting on the rear edge of the slot 110 to hold the trap door 95 in closing position with respect to the hole 97 in the board 20.

Under each hole 90 in the board 20 the plate 75 102 is formed with a slot 111. Below the slot

87 the plate 102 has a complementary slot 112 normally disposed forwardly of the slot 87 as appears in Figure 9. Under the holes 45, 46 the plate 102 has a slot 113 and under the holes 57, 58 the plate 102 has a slot 114. Similarly, under 5 the cannon 68 and trap door 49 is a slot 115 in the plate 102 including a cross bar 116 to carry the tail of the trap door 49. In the same fashion the plate 102 has a slot 117 and bar 118 under the cannon 60 and trap door 61. Still further 10 there are large cut outs 119 in the plate 102 under the hoods 28, 29 and 30, 31 to accommodate the catapults later to be described. The other hoods 27, 32 are disposed laterally of the side edges of the plate 102 as shown in Figure 2. 15

As shown in Figures 2 and 9 the under side of the plate 102 carries depending studs 120 for slidably mounting a triangularly shaped thin sub-plate 121 under the main plate 102. The sub-plate 121 has slots 122 to permit the sub-plate 20 121 to slide on the studs 120 independently of the main plate 102.

In Figure 8 it will be seen that the front end of the sub-plate 121 carries an upstanding striker 123 which passes upwardly through the slot 108 in 25 the plate 102, through the slot 66 in the board 20 and into the gun barrel 63.

The lower or front edge of this sub-plate 121 is shaped to avoid the slots 111 and holes 107 as shown in Figure 2. At each front corner the 30 plate 121 has pivotally connected to it, as shown in Figure 5, a laterally extending link 124 to the outer ends of which are made fast the vertical rock shafts 99. A pair of springs 125 are suitably connected between the sub-plate 121 and the 35 main plate 102 as shown.

Also as shown in Figures 2 and 9 at its front end the plate 102 carries pins 126 on its under side to slidably support in the same manner a pair of small elongated plates 127, one on each side, said 40 plates extending under the slots 25 in the board 20. These smaller sub-plates 127 each extend respectively under the two gun barrels 60 and in the same manner as the plate 121 at their rear ends carry an upstanding striker 128. Links 45 129 connect the sub-plates 127 with the sub-plate 121 for conjoint shifting movement.

These sub-plates 121, 127 are shifted electrically by the action of a solenoid 130 fastened to the rear wall 17, the circuit for the solenoid normally being open, but closed when a ball dropping through either hole 66, 68 closes a circuit maker now to be described.

By means of side rails 131 the cabinet carries a bottom sloped, stationary panel 132 shown best 55 in Figures 6 and 9. At its upper, or rear end the panel is formed with a groove 133 in which is mounted a long flat spring circuit maker 134 (see also Figure 11). This spring is secured in place by a binding post 135 connected by an electric 60 wire 136 to the solenoid 130 as shown also in Figure 2. The spring 134 includes a contact 137 to engage a binding post 138 wired by a lead 139 to a battery 140. Adjacent the groove 133 is a parallel groove 141 in the panel 132 that communicates with the first groove 134, as shown, said groove 141 being directly under the holes 66, 68 so that when a ball drops through either of said holes it falls into the groove 141 and then rolls into the groove 133 and over the front end 70 of the flat spring 134. The weight of the ball, of course, closes the contacts 137, 138 to close the circuit described.

This energizes the solenoid causing its armature 142 as shown in Figure 8, to pull a link 143 75

slidingly mounted in a guide 144. The front end of the link 143 has an upstanding arm 145 to engage a bracket 146 secured to the under side of the sub-plate 121. Consequently said plate is pulled rearwardly toward the solenoid 130 causing the striker 123 to project a ball lodged on the trap door 64 uphill on the board. The sub-plate 121 also moves the links 124 to rock the shaft 99 to actuate the bell crank switches 108. At the same time through the links 129 the sub-plates 127 are pulled rearwardly to cause the strikers 128 to shoot balls uphill from the guns 48 and 60. These plates 127 also are shifted away from under the holes 25 to permit balls lodged therein to drop through the board 20 for free replay as will later appear.

This shifting of the sub-plates is against the pull of the springs 125, the forward movement being cushioned when a bracket 147 (see Figure 8) strikes a cushion spring 148 on the guide 144. The circuit is instantly broken when the ball rolls off the contact spring 134 whereupon the springs 125 are instantly operative to return the sub-plates and connected parts to normal position. The return movement of these sub-plates is stopped by a bracket 149 carried on a cross bar 150 which also carries the guide 144. The bar 150 is mounted on the cabinet sides as shown in Figures 8 and 9 by brackets 151.

As shown best in Figure 6 the panel 132 is formed with a plurality of grooves to lead balls dropping through the top board 20 and plate 102 to the front edge of the panel 132. For example, a groove 152 receives balls dropping through the holes 69 and 94. A groove 153 receives balls falling from the seat 72 in hole 71 and complementary hole 106 in the plate 102, as well as balls released through the slot 97 off door 95 at the left hand side of the game.

A groove 154 takes balls dropping through the holes 57, 58, while a groove 155 receives balls dropping through the left hand hole 90 in the zone 84. A bifurcated groove 156 receives balls from the seats 89 in holes 88 that drop through the complementary holes 107 in the plate 102. The groove 133 runs into the groove 156 as shown, while a ball released through the trap door 64 falls through slot 108 in plate 102 into an extension 157 of the groove 156 as shown in Figure 6. In a similar fashion balls dropping through the right hand hole 90 fall into a groove 158; balls dropping through holes 45, 46 fall into a groove 159; a ball dropping from the seat 74 in hole 73 falls into a groove 160; and balls dropping through the holes 70 and the right hand hole 95 fall into the groove 161. These grooves just described lead the balls either to a ball accumulating trough or to any one of a series of catapults, which latter mechanism will next be described.

The side walls of the cabinet carry a transverse rock shaft 162 in a position just off the end and forwardly of the front edge of the panel 132 as shown in Figures 6, 9 and 10. Firmly secured to said shaft 162 are forwardly inclined channel-shaped ball receiving catapult members 163, there being one such catapult disposed directly beneath the respective hoods 27, 28, 29, 30, 31 and 32 heretofore described.

Each catapult channel 163 carries a circuit breaker comprising a flat spring finger 164 secured to the bottom of the channel on the top surface thereof, while on its under surface the channel carries a complementary spring finger 165 with an insulator strip 166 separating the two as shown in Figure 10. The front ends of

the springs may contact through an opening 167 in the bottom of the catapult. An electric wire 168 connects all of the lower contact springs 165 in series, there being slack in the wire between adjacent catapults as indicated in Figure 6. This wire then goes from the left hand catapult 163 to a solenoid 169 secured to the front wall 16 of the cabinet. Another wire 170 leads from the solenoid 169 to the battery 140 heretofore de-

scribed. The metallic rock shaft 162 is connected by a wire 171 with the battery 140. Thus, when a ball rolls onto any catapult 163 the contacts 164, 165 close the circuit to energize the solenoid 169. This draws the armature 172 forwardly to pull on a link 173 pivoted thereto and also pivoted to a link 174 secured to the rock shaft 162. Such action rocks the shaft 162 to swing all the catapults simultaneously upwardly and rearwardly as shown in the dotted lines in Figure 9 to project balls thereon uphill on the board 20 from under the several hoods 27 to 32 inclusive. As soon as the ball leaves the catapult the springs 164, 165 separate to open the circuit whereupon the unbalanced weight of the catapults causes reverse rocking movement of the shaft 162 to restore the catapults in the ball receiving position shown in Figure 10.

From the showing of Figure 6 it will now be clear that a ball rolling down the groove 152 must roll onto the catapult 163 in line therewith; the groove 154 leads to a catapult, as do respectively the grooves 155, 158, 159 and 161. Balls rolling down the other grooves 153, 156, and 160 roll over the shaft 162 and fall onto a chute 176 carried on a support 175 mounted on the floor 18. Said support 175 and chute 176 are appropriately slotted to accommodate the links 173 and 174 as shown in Figure 10.

The chute 176 directs the balls into a transverse trough 177 which is inclined from left to right to direct the balls to a ball lifter 178 operated manually by a conventional pusher 179 carried in the front wall 16. This elevator is of well known form and lifts the balls one at a time from the lower end of the trough 177 into position in the passage 35 to be projected by the shooter 37 in a manner well understood in this art. Another chute 180 returns balls dropping through the slots 25 and 26 to the trough 177. This completes the description of the structural parts of the game, and the manner of playing the same, and its operation will next be taken up.

We will assume the slide 105 has been coin released, as intended, and that all of the ten balls sealed in the cabinet have been delivered to the trough 177. The parts are then as shown in Figures 1, 2 and 9 which may be called the game starting position. The player at the front end of the cabinet operates the lifter 178 by the pusher 179 to raise the balls one at a time into position on the board 20 to be projected by the shooter 37, all as is common in the art.

The projected balls from the shooter 37 move through the passage 35 into the top zone 63'. In successively shooting the balls we will assume that several of them gravitate into the passage 93 onto the door 95 therein. The gate 100 is in position to hold the balls from rolling to the hole 94 as shown in Figure 3. If now a ball drops through the control hole 68 the circuit maker of Figure 11 becomes operative causing the solenoid 130 to pull the sub-plate 121 rearwardly. This rocks the shaft 99 through the link 124 (see Figure 5) to move the bell crank gate or switch from

the ball holding position of Figure 3 to the ball releasing position of Figure 4. The switch is so constructed that only one ball at a time is released for down-hill gravitation through the passage 93 to the hole 94. This is one way for a ball to get out of the zone 63'. Of course, the instant this has happened the circuit maker 137, 138 has opened because it is only closed for the instant the ball rolls over the strip 134. Thereupon the springs 125 are immediately operative to restore the sub-plate 121 to its normal position. This restores the switch 109 to its normal position shown in Figure 3.

Now let us consider what happened to the ball 15 that left zone 63' by falling through the hole 94. Obviously, the groove 152 under the hole 94 received this ball and caused it to roll onto the catapult 163 under the hood 27. As shown in Figure 10 the weight of the ball closes the circuit 20 maker 164, 165 in the catapult to energize the solenoid 169 causing the linkage 173, 174 to rock the shaft 162 carrying said catapult. Thus the catapult mentioned, and as a matter of fact, all of the others too, swings upwardly and rearwardly through a hole 33 in the board to the dotted line position of Figure 9. Obviously, the ball we are discussing will thus be catapulted or thrown up through the board 20 and rearwardly, or uphill thereon into the zone 56 through 30 the passage 52.

Several things might happen to this same ball in zone 56. For instance, if it drops through the hole 57 it passes through the slot 114 in the plate 102 and into the groove 154 which causes 35 it to roll into the catapult 163 under the hood 28. Again the circuit is made to cause the catapults to swing with the shaft 162, whereupon the particular catapult under the hood 28 throws the said ball up through cut out 119 in the plate 102, through the aligned hole 33 in the board 20 and rearwardly out from under the hood 28 to roll the ball back, or uphill on the board 20 through the passage 85 and into the progressively higher scoring zone 84.

Assuming that the same ball now drops 40 through the hole 90 on the left hand side of the zone 84 then it is taken by the groove 155 in the panel 132 and led to the catapult under the hood 29. Said catapult in the manner described catapults the said ball back onto the passage 80 whereupon the ball gravitates from the highest scoring zone 78 downhill into the main object or goal pocket 26, where the ball is supported by the plate 102 thereunder. In the manner thus described any ball may be moved 45 successively from the zone 63 to the zones 56 or 43; thence to zone 84; and finally to zone 78 and the ultimate object pocket 26. The design 50 of the zones and ball trapping and moving mechanism is symmetrical on opposite sides of the longitudinal center of the game, so that obviously both sides thereof function alike.

Other things can happen to a ball in the zone 63'. For instance, it could drop through one of the holes 69, into groove 152 and actuate the same catapult set into operation by balls from the hole 94 and the same successive movement thereof through the several zones, as has been described, is possible. A ball dropping through the holes 70 does the same thing except on the right hand side of the game, the groove 161 taking the ball in such case.

If a ball falls into the holes 71, 73 in said zone 63' the seats 72, 74 therein hold the ball 75

and thus balls in said holes are held against any further action.

Another possibility in the zone 63' is for a ball to lodge on the seat 64 adjacent the muzzle end of the gun 63. Thereafter if a subsequent 5 ball is dropped through the hole 68 the solenoid 130, in the manner already described, is operative to shift the sub-plate 121 to operate the striker 123, whereupon the ball on the seat or trap door 64 is back rolled uphill into the hole 10 66. As the ball drops through hole 66 it causes a repeat operation of the solenoid 130 once more to operate all parts connected with the sub-plate 121, as for example the gate switches 100. The balls which drop through the control holes 66, 15 68 roll down the groove 133 and 156 to the lower end of the board 132 where they jump or roll over the shaft 162 onto the chute 173 for delivery into the trough 177 for free replay in a manner 20 that will be readily understood.

Other things than have been described may happen to balls getting into the zone 56 from the projection passage 52. For instance, a ball might lodge on the trap door 61 adjacent the gun 60 and be fired uphill to the hole 58 when 25 another ball drops through either hole 66, 68 to operate the solenoid 130. As has been described, this shifts the sub-plate 121 and, of course, with it the connected sub-plate 127, thus moving the striker 128 for the gun 60. The ball dropping 30 thus through the hole 58 moves to a catapult by means of the groove 154 to be catapulted into the succeeding zone 84.

Still another thing can happen in zone 56, for a ball can lodge in the pocket 25 where it is 35 supported by the sub-plate 127. However, every time the sub-plate 127 is shifted such balls contained in the pocket 25 would be returned to the trough 177 for free replay. The same possibilities for action may occur in the right hand 40 corresponding zone 43.

In considering the zone 84 there was described what happens to a ball falling through either hole 90. In addition other things could happen to balls in this zone 84. For instance, balls may 45 be taken out of play against further movement should they lodge on any of the seats 89 in the holes 88; or balls in said zone may be taken out of play by gravitating into the slot 87 where they remain supported by the plate 102. 50

This takes care of all possibilities of action and quite obviously it must now be appreciated that the mechanism provides an unusual player interest. Eventually all of the predetermined number of balls which, as has been said is ten, 55 are lodged in out of further play positions, as for example, in the pockets 25, 26, 87, 89, 72, 74 or on any of the trap doors 64, 95, 49 and 61. Such balls are restored or returned to the trough 177 for a subsequent play cycle by actuating 60 the coin release slide 105 which abuts the bracket 104 to shift the plate 102 rearwardly. Such action removes the support from under each of the doors 64, 95, 49 and 61 so that balls thereon drop respectively through openings 108, 110, 115 and 65 117 in the plate 102 and into the ball return grooves 157, 158 for the door 64; into grooves 153 and 160 for the doors 95; into groove 153 for the door 61; and into groove 160 for the door 49.

At the same time while the plate 102 is so 70 shifted the ball falls off seat 72 in hole 71 to drop through hole 106 in plate 102 and into groove 153 for return to the trough 177; while a ball from the seat 74 in the hole 73 falls through the adjacent hole 106 in the plate 102 to 75

fall into the groove 160 for return to said trough 177. Balls from the seats 89 in the three holes 88 fall through the adjacent holes 107 in the plate 102 and drop into the bifurcated groove 156 for return to the ball delivery trough 177.

5 Balls from the pocket 87 fall through the hole 112 in plate 102 and thence into the groove 156; while those balls in the pocket 26 drop onto the chute 180. As the plate 102 is manually shifted 10 it picks up the sub-plates 127 to shift them from under the holes 25 to cause return of any balls 15 that may be therein. This accounts for all ten balls and the action described, of course, takes place instantly when the plate 102 is shifted. Any 15 conventional spring means, not shown, serves to return the plate 102 to its forward, game playing position. The game is now ready for another play cycle.

It is the intention to cover all changes and 20 modifications not departing from the spirit and scope of the invention, as indicated by the following claims.

What is claimed is:

1. A game comprising a board inclined from 25 the horizontal and having a plurality of holes formed therethrough, means for projecting balls over the board to fall through said holes, an inclined panel below the board having alleyways thereon to receive the balls dropping through 30 said holes, a cross shaft adjacent the lower edge of the panel having swingable members thereon to receive the balls from the alleyways, and means to swing said members simultaneously to throw the balls upwardly back onto the board to roll 35 them uphill thereon.

2. A game comprising a board inclined from the horizontal and having a plurality of holes formed therethrough, means for projecting balls over the board to fall through said holes, an inclined panel below the board having alleyways 40 thereon to receive the balls dropping through said holes, a cross rock shaft adjacent the lower edge of the panel, catapult members fastened to said shaft, one for each of the alleyways to receive the 45 balls respectively therefrom, and electrical means controlled by a ball rolling onto a catapult member to simultaneously rock the shaft and the catapults to cause the balls to be thrown back onto the board and to be rolled uphill thereon.

50 3. A game comprising an inclined game board segregated on its top surface into separate ball rolling zones, means for rolling a ball into one of said zones, said ball falling through a hole formed

in the said one of said zones, and means for then successively causing said ball to be elevated and thrown into another of said zones, there being a hole in said last named zone through which the ball may drop, said means thereupon adapted again to elevate the ball and throw it into still another of said zones.

4. In a game of the character described, an elongated, longitudinally inclined, playing board having a plurality of ball retaining holes therein and also having an additional hole and a special hole through which a ball projected onto the board may drop, means for projecting a group of balls, one at a time over the board for gravitation down the board, releasable means for holding a ball in said additional hole, means for automatically releasing said holding means when a ball drops through the special hole, the combination with said board of means for automatically discharging back onto the board for roll toward 20 the ball retaining holes a ball released from said additional hole as the result of release of said holding means.

5. In a game of the character described, an inclined board having a plurality of ball retaining 25 holes therein and also having releasable means for retaining a ball projected over the board, means for projecting a group of balls, one at a time, over the board for gravitation down the board, means controlled by a ball in play for 30 releasing the ball retaining means, the combination with said board of automatic means for propelling in the direction of said retaining holes a ball released by said retaining means.

6. A game board of the character shown and 35 described and having openings therethrough for balls to roll into, a sliding panel thereunder for holding said balls in said openings, means for impelling a ball onto said board, means for moving said panel to release balls in said openings, 40 boundary means dividing said board into different areas or zones to prevent balls from rolling from one of said areas into another area while rolling on the surface, ball-impeller means under 45 said board operable by action of a ball rolling to said board to impel the ball upwardly through said board, means under said board for receiving balls through certain of the openings in said board and guiding them to said ball impeller, whereby said ball is impelled through said board 50 within one of said areas.
